Falling Leaves Stained Glass Panel, Mar. 19, 2009, http://etsyglass.blogspot.com/2009_03_01_archive.html.*Primary Examiner — Angela J Lee*(74) Attorney, Agent, or Firm* — Berenato & White, LLC(57) **CLAIM**

The ornamental design for a light panel, as shown and described.

DESCRIPTION

FIG. 1 is a front elevational view of a first embodiment of my design;

FIG. 2 is a cross-sectional view taken along the line 2-2 of FIG. 1;

FIG. 3 is a cross-sectional view taken along the line 3-3 of FIG. 1;

FIG. 3A is an enlarged view of a detail of FIG. 3;

FIG. 4 is a front elevational view of a second embodiment of my design;

FIG. 5 is a cross-sectional view taken along the line 5-5 of FIG. 4;

FIG. 6 is a cross-sectional view taken along the line 6-6 of FIG. 4;

FIG. 6A is an enlarged view of a detail of FIG. 6;

FIG. 7 is a front elevational view of a third embodiment of my design;

FIG. 8 is a cross-sectional view taken along the line 8-8 of FIG. 7;

FIG. 9 is a cross-sectional view taken along the line 9-9 of FIG. 7; and,

FIG. 9A is an enlarged view of a detail of FIG. 9.
